(57) **CLAIM**

The ornamental design for a laryngoscope blade, as shown and described.

DESCRIPTION

FIG. 1 is one perspective view of a laryngoscope blade with the design;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines shown on the drawing depict portions of the laryngoscope blade that form no part of the claimed design. The alternating length broken lines immediately adjacent the shaded surfaces depict the boundaries of the claimed design, and also form no part of the claimed design.
